United States Patent Office

Des. 176,759
Patented Jan. 31, 1956

176,759

HOOK OR SIMILAR ARTICLE

Joseph Frank, Forest Hills, N. Y., assignor to Trulon Corporation, Elmhurst, N. Y., a corporation of New York

Application May 16, 1955, Serial No. 35,996

Term of patent 7 years

(Cl. D17—12)

FIG. 1.

FIG. 2.

FIG. 3.

FIG. 4.

Fig. 1 is a perspective view of a hook or similar article showing my new design.

Fig. 2 is a plan view of the hook.

Fig. 3 is a front view of the hook.

Fig. 4 is a perspective view thereof in an inverted position.

The broken lines are for the purpose of illustration only.

I claim:

The ornamental design for a hook or similar article, as shown and described.
